(57) **CLAIM**

The ornamental design for an accessory for a mobile device, as shown and described.

DESCRIPTION

FIG. 1 shows a top perspective view of the front-left of an accessory for a mobile device.

FIG. 2 shows a top perspective view of the back-right of the accessory for a mobile device.

FIG. 3 shows a top view of the accessory for a mobile device.

FIG. 4 shows a bottom view of the accessory for a mobile device.

FIG. 5 shows a right-side view of the accessory for a mobile device.

FIG. 6 shows a left-side view of the accessory for a mobile device.

FIG. 7 shows a rear view of the accessory for a mobile device.

FIG. 8 shows a front view of the accessory for a mobile device; and,

FIG. 9 shows a bottom perspective view of the front-left of the accessory for a mobile device.

The consistent broken lines in the drawings are for the purpose of illustrating portions of the accessory for a mobile device and form no part of the claimed design.

1 Claim, 9 Drawing Sheets
